The ornamental design for cellular phone carrying case, as shown and described.

DESCRIPTION

FIG. 1 is a front view of the cellular phone carrying case of the invention.

FIG. 2 is a right side view of the cellular phone carrying case of FIG. 1.

FIG. 3 is a rear view of the cellular phone carrying case of FIG. 1.

FIG. 4 is a top view of the cellular phone carrying case of FIG. 1.

FIG. 5 is a bottom view of the cellular phone carrying case of FIG. 1.

FIG. 6 is a front view of the cellular phone carrying case of FIG. 1, but shows a cellular phone in phantom being carried therein.

FIG. 7 is a right side view of the cellular phone carrying case of FIG. 1, but shows a cellular phone in phantom being carried therein; and,

FIG. 8 is a back view of the cellular phone carrying case of FIG. 1, but shows a cellular phone in phantom being carried therein.

The broken lines shown on the case represent topstitching. The left side view of the cellular phone carrying case (not shown) is a mirror image of the right side view shown in FIG. 2. The cellular phone shown in phantom in FIGS. 6-8 forms no part of the design.
